(57) **CLAIM**

The ornamental design for the folding toilet as shown and described.

DESCRIPTION

FIG. 1. is a perspective view of a folding toilet showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof;

FIG. 9. is a detail view thereof;

FIG. 10. is a second detail view thereof;

FIG. 11. is a third detail view thereof;

FIG. 12. is a perspective view showing the design in a closed position; and,

FIG. 13. is perspective view showing the design in a folded position.

The broken lines depict surface shading or structural portions of the folding toilet that form no part of the claimed design.

1 Claim, 13 Drawing Sheets
